UNITED STATES PATENT OFFICE.

FRANCIS DELOS RAPPELEE, OF GREEN BAY, WISCONSIN.

CAMP-BED.

No. 835,469.

Specification of Letters Patent.

Patented Nov. 6, 1906.

Application filed February 20, 1906. Serial No. 302,098.

To all whom it may concern:

Be it known that I, FRANCIS DELOS RAPPELEE, a citizen of the United States, and a resident of Green Bay, in the county of 5 Brown and State of Wisconsin, have invented a new and useful Improvement in Camp-Beds, of which the following is a full, clear, and exact description.

The purpose of the invention is to provide 10 a simple, comfortable, and economic form of camp or field bed, and to so construct the same that it can be compactly folded for storage and transportation, quickly set up for use, and so that all parts will remain connected at all times.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the improved bed drawn upon a small scale. Fig. 2 is a side elevation thereof, a part appearing in section. Fig. 3 is a transverse section through the bed. Fig. 4 is an inner face view of an end member of the bed, a part being in section and the canvas being removed. Fig. 5 is a vertical section through an end portion or member of the bed, the section being taken practically on the line 5-5 of Fig. 4 and a sectional side elevation of the anchoring device for the bed. Fig. 6 is a vertical longitudinal section through a metal end portion of the bed, and Fig. 7 is a vertical transverse section taken practically on the line 7-7 of Fig. 6.

The bed is provided with two end portions A, which may be termed "head" and "foot" sections, and both of these portions are of the same construction. Ordinarily these end portions are made of wood, as illustrated in 45 Figs. 1, 2, 3, 4, and 5, and each end portion A of the bed is made in two sections 10 and 11, connected by a hinge 12, which hinge is located at the bottom face of the central part of the end portion of the bed, as is best shown 50 in Figs. 3 and 4.

A long staple 13 is suitably secured to the inner face of the sections 10 and 11 of the end portions of the bed, and these staples are passed through hems 14, formed at the ends 55 of the canvas or fabric body B of the bed.

The end or head and foot portions of the bed are supported by legs 15, which legs are given an inclination from the top downward and outward, so as to provide firm supports for the bed, and each leg 15 is provided with a 60 tenon 16 at its upper end, and the tenons 16 of the legs are made to enter inclined openings 17, produced adjacent to the outer ends of the said sections 10 and 11 of the head and foot portions of the bed.

In order that the legs 15 when removed from the sections 10 and 11 shall not be lost and will always be at hand, they are connected with said sections by lengths of rope 18, chain, or the like.

A series of hems 20 is formed at each side of the body B, and ropes 20 are passed through these hems and through suitable openings in the outer ends of the head and foot sections 10 and 11, and these ropes 20 are made to extend beyond the said head and foot portions of the bed, and are connected so as to form stay-sections 20^a, which stay-sections of the ropes 20 are suitably attached to the anchors C. The sections 20^a of the 80 rope 20 are passed through eyes 21, formed upon the bolts 22, which bolts 22 are mounted to slide in vertical slots 23, made in the upper portion of the anchors C, so that the extension-ropes 20^a will be under proper tension whether the anchors are driven deeply 85 into the ground or not.

In the construction of the anchors C their lower portions 24 are hollow and conical, their lower extremities being quite sharp, 90 and the upper slotted portions of the anchors are strengthened by concaved wings 26 at the side edges, constituting integral portions of the anchor. At the upper end of each anchor an enlargement 27 is made adapted to 95 be struck when the anchor is driven into the ground.

Auxiliary legs 28 are provided between the head and foot portions A of the bed, and these auxiliary legs 28 are provided with 100 metal straps 29 at their upper ends, through which straps the side ropes 20 of the body of the bed are passed. Corresponding legs at opposite sides are preferably made to meet each other about centrally beneath the body 105 of the bed, and have interlocking connection 30, as is shown in Fig. 3.

In Figs. 6 and 7 I have illustrated a head and foot portion of a bed constructed of metal. These head and foot portions A' are 110.

also in two sections 10^a and 11^a, the sections being connected at the center of the said head and foot portions by means of suitable hinges 12^a. These metal portions A' are 5 made of channel-iron and are open at their lower edges, as is shown in Fig. 7, and the legs 15 are flat, and are likewise made of metal. Each leg 15^a, which fit between the flanges or members of the said portions, is 10 provided with a slot 31 at its upper portion, and in the outer marginal edge adjacent to the said slot 31 a finger 32 is longitudinally formed. When the legs are in their supporting position, they incline downward and outward and their upper ends enter depressions 15 33, made in the top of the sections 10^a and 11^a, as is best shown in Fig. 6.

A pivot-pin 34 is passed through the slot 31 of each leg 15^a, and other pins 35 are provided adjacent to the pins 34, adapted when the legs are in their supporting position to enter the spaces between the body portions of the legs and the fingers 32. The pins 34 and 35 pass through from one side of a section 25 to the other, as is shown in Fig. 7. Thus, it will be observed, as indicated by dotted lines in Fig. 6, the legs 15^a may be folded up in the space between the members of the parts A' and be entirely out of the way and that 30 when a bed is to be set up by simply dropping the legs downward they automatically assume the locked position shown in Fig. 6.

The anchorage for this bed is the same as has been described, and the body portion of 35 the bed is likewise of the same construction, staples 13^a being provided for the parts A' to receive the end hem 14 for the body B.

In order to prevent the bottom portions of 40 the legs entering the ground when the bed is occupied or set up, feet 37 are provided for said legs, which feet consist of blocks of metal or of wood, having hooks 38 attached thereto, which hooks are adapted to pass through and have sliding movement in slots 45 36 at the bottom of the said legs, so that when the feet 37 are not needed they can be folded up along the side of the legs, as shown by dotted lines in Fig. 7.

This bed is particularly adapted for camping 50 out or for the use of soldiers. It is very strong, comfortable to lie upon, can be quickly set up or taken down, and when not needed it can be folded compactly. At the same time, since all of the parts are connected 55 they are not liable to become lost and are always at hand when needed.

Having thus described my invention, I claim as new and desire to secure by Letters Patent—

60 1. A camp-bed, consisting of head and foot portions comprising each a top bar in two hinge-connected sections and folding legs, a canvas body attached at its ends to the upper bars of the said head and foot portions, and 65 side supporting-cables for the said body,

which cables are carried through the bars of the head and foot portions for attachment to an anchoring device.

2. A camp-bed, comprising head and foot members, each consisting of a top bar constructed in hinge-connected sections and adjustable legs, a fabric body, means for connecting the fabric body to the top bars of the head and foot members, supporting-cables connected with the sides of the said body, which cables are carried through the head and foot sections for attachment to anchoring devices, and adjustable auxiliary legs pivotally connected to the side or supporting cables and adapted to be carried below the 75 said body to a point near the center thereof, and transversely-opposing legs having their lower ends brought together.

3. In a camp-bed, a head and a foot portion constructed in hinge-connected sections, 85 legs pivotally attached to the said sections, locking devices for the said legs, a fabric body, means for connecting the fabric body to said head and foot portions, and supporting-cables for the sides of the said body, which 90 cables extend beyond the said head and foot portions for attachment to an anchoring device.

4. In a camp-bed, a head and a foot portion, a fabric body, means for attaching the fabric body to the said head and foot portions, supporting-cables for the sides of the said body, which cables extend beyond the outer faces of the said head and foot portions, anchors having slots therein, and eye-bolts adjustable in said anchors, which eye-bolts are connected with the extension portions of the said supporting-cables.

5. In camp-beds and the like, an anchor therefor having a conical tubular lower portion and an upper substantially straight portion having a longitudinal slot therein, and an eyebolt held to travel in the said slot.

6. In a camp-bed, head and foot portions, ropes connecting the head and foot portions and legs having eyes at their upper ends through which the said ropes pass, said legs being inclined inwardly toward each other and having interlocking engagement.

7. In a camp-bed head and foot portions 115 inverted-U shape in cross-section, side members connecting the head and foot portions, and legs pivoted between the members of the head and foot portions.

8. In a camp-bed, head and foot portions 120 inverted-U shape in cross-section and having pins extending between the members thereof, side members connecting the said head and foot portions, and legs each provided with a slot and a finger engaging the pins of the 125 head and foot portions.

9. In a camp-bed, head and foot portions 130 inverted-U shape in cross-section, said portions having pins extending between the members thereof, and provided with de-

pressions in the under faces of their tops, and legs having their upper ends entering the depressions of the head and foot portions and each provided with a slot and a finger 5 engaging the said pins.

10. In a camp-bed, head and foot portions, side members connecting the head and foot portions, legs secured to the head and foot portions and having their lower ends slotted,

and feet provided with hooks engaging the 10 slots of the legs.

In testimony whereof I have signed my name to this specification in the presence of two subscribing witnesses.

FRANCIS DELOS RAPPELEE.
